CURTAIN ROD OR THE LIKE

Roy L. Brenner, Deerfield, Ill., assignor to Kinhead Industries Incorporated, Chicago, Ill., a corporation of Illinois

Filed Jan. 21, 1963, Ser. No. 73,262

Term of patent 14 years

(Cl. D21—1)

The broken line illustration of a curtain in FIGURE 1 is for illustrative purposes only.

I claim:

The ornamental design for a curtain rod or the like, substantially as shown and described.
